(57) **CLAIM**

The ornamental design for a bottle combination, as shown and described.

DESCRIPTION

FIG. 1 is a perspective view of the bottle combination;
FIG. 2 is a front elevational view of the present invention;
FIG. 3 is a rear elevational view of the present invention;
FIG. 4 is a left side elevational view of the present invention,
the right side elevational view being a mirror image thereof;
FIG. 5 is a top plan view of the present invention; and,
FIG. 6 is a bottom plan view of the present invention.
The broken lines in the drawings illustrate the portions of the
bottle combination that form no part of the claim.
